UNITED STATES PATENT OFFICE

2,578,225

FEEDING DEVICE FOR SEWING MACHINES

Ramon Casas Robert and Jean Court, Geneva, Switzerland, assignors to Mefina S. A., Binningen, Switzerland, a corporation of Switzerland

Application March 31, 1949, Serial No. 84,610
In Switzerland December 20, 1948

5 Claims. (Cl. 112—210)

1

The present invention relates to an actuating mechanism for the feeder of a sewing machine which differs from the known mechanisms by the fact that the said feeder is carried by a support connected to an actuating element by means of two levers, the first one of which is rigid and rocks around a fixed vertical axle, while the second one is elastic, in order to enable it to follow the displacement of the first one and rocks around a fixed horizontal axle.

The attached drawing shows diagrammatically and by way of example a form of execution of the mechanism.

Fig. 1 is a perspective view;

Fig. 2 is a side view;

Fig. 3 is a top view of the mechanisms housed in the lower arm of the sewing machine;

Fig. 4 is a vertical section view of the column of the machine.

As shown in the attached drawing, the actuating mechanism for the feeder or feeding device 1 includes a cam 2 rigidly fixed to a shaft 3 driven in rotation by a driving shaft P of the sewing machine through a belt B. This cam 2 is connected to the feeder by two transmission levers, of which one imparts to it a rocking movement in a horizontal plane and the other, a rocking movement in a vertical plane.

The first transmission device includes a boss 4 carried at one end of a first arm 5 and in which is fixed an axle 6 of which the ends slide into bores or guides g provided in the two branches of a support 7 having the general form of a U. The feeder 1 is rigidly fixed on the upper face 8 of the support 7. The arm 5 has, at its end opposite to that carrying the boss 4, two branches 9 (Fig. 2) arranged in the form of a fork and between which is engaged one of the ends of a second arm 10. These two arms 5 and 10 are rigidly connected one to the other by an adjusting and locking element 11 to form a lever rockably mounted on a common fulcrum axle 12, of which the ends are rigidly fixed in the branches of a support 13 rigidly fastened to the frame 14 of the machine by means of fastening elements v. The arm 10 carries two guides 15 and 16 (Fig. 3) into which slides a rod 17 carrying a driving carriage 18. The latter has:

(1) A guiding finger 19 sliding into a guide 20 carried by the guide 16 of arm 10;

(2) A cam following surface 21 kept in contact with the profile of the cam 2 by a spring 22 mounted on the rod 17 and resting, on the one hand, on face 23 of guide 16, fastened to the arm 10 and, on the other hand, on a stop 24 fixed to the rod 17;

2

(3) A part 25 slidably engaged in a slot provided in a guide 26 fastened on the end of a control shaft s, of which the angular position can be chosen and fixed at will by means of a controlling member O having a cam surface b engaged by the end of a lever f fixed on shafts and urged against cam b by a spring j.

The second transmission device includes a lever consisting of an elastic blade 27 in one end of which is cut out a tongue 36 of triangular form. The blade 27 and tongue 36 are secured to a part 28 by means of a bridge 37 and rivets 42. The part 28 has the shape of a U, of which the two wings are connected together by one of the arms 15 of an L-shaped part 29. The second arm of this part 29 serves as an actuating finger 30 kept in contact with the profile of the cam 2 by a coil spring 31. The tongue 36 carries an axle 32 freely pivoted in a bearing 40 carried in the support 13. This axle 32 is horizontal and is kept in position in the bearing 40 by a stop element 41.

The finger 30 is engaged in a guide provided by a slot 38 in the free end of a rod 39, rigidly fastened to the frame of the machine, and on which is mounted the return spring 31. The end of the elastic blade 27 has a notch 33 in which is engaged the end of an axle 34 freely mounted in the bore of a boss 35 provided in the support 7.

The operation of the described mechanism is as follows:

When the cam 2 is driven in rotation, it actuates simultaneously the finger 30 and the follower 21 against the actions of the return springs 22 and 31. The guide 26 being positioned with its slot inclined in relation to a plane perpendicular to the driving shaft 3 and the part 25 being compelled to follow the slot in the guide 26, the reciprocation of the cam follower 21 causes the rocking of the lever 5, 10 about the vertical axle 12. Thus, the guide 4 is actuated in a to and fro movement in a horizontal plane and carries the support 7 along with it by means of the axle 6 engaged in the guides g. The end of the blade 27 is oscillated by the movements of supports 7 against its elastic action which tends to keep said blade in the plane of the tongue 36 which is held on axle 32 and in the slot 38. The actuating of the finger 30 by cam 2 causes the rocking in a vertical plane of the lever, composed of the parts 27, 28, 29 and 36, around the axis of the horizontal axle 32. This rocking movement is effected against the action of the return spring 31.

Thus, the axle 43 is driven in a rocking movement in a vertical plane and due to the resilient

nature of arm 27, it can follow the horizontal rocking movement imparted to the axle 6 by lever 5, 10.

From the above explanations and by examining the attached drawing, it can be seen that the support 7 is connected to the cam 2 by means of two levers, of which the first one 5, 10 is rigid and rocks around a fixed axle 12, while the second one (27, 28, 29, 30 and 36) is elastic and rocks about the horizontal axis 32 of the bearing 48. The two rocking movements imparted to the support 7 being effected by a single cam 2, their synchronism is automatically ensured. Finally, by modifying the inclination of the slot in the guide 26 in relation to a plane perpendicular to the shaft 3 by rocking the controlling element O, it is possible to modify, to reverse or even to eliminate the extent of the horizontal to and fro movement of the axle 6 and therefore to fix at will the direction and the pitch of the advancement of the cloth by the feeder 1.

In addition, as shown on the drawing, the points of contact on the cam 2 of the finger 30 and of the cam follower 21 are spaced angularly by about 90°, so that the two rocking movements are dephased by 90°. Lastly, the surfaces *r* of this cam are connected together by surfaces *m* having the form of arcs of circles centered on the rotation axis of the cam, the result is that the arms are alternately driven, so that the feeder is displaced by the actuating mechanism along an approximately rectangular path, and that it is always displaced horizontally and at a constant height over practically all the length of its advancement stroke, irrespective of the extent of said stroke over the upper or lower level of the work plate *w*. This feature is also of great importance, because it ensures an absolutely regular feeding of the cloth and avoids any stretching of the latter.

The bore made in the arm 9 for the screw 11 has a dimension sufficient to permit the adjusting at the factory of the horizontal position of the feeder 1 in relation to the needle N for a given position of the cam 2.

A form of construction of the actuating mechanism for the feeder of a sewing machine has been described here by way of example and with reference to the attached drawing, but it is obvious that all the described parts can be simply replaced by their equivalents.

We claim:

1. An actuating mechanism for the feeding device of a sewing machine comprising a driving element, a rigid lever mounted for rocking movement about a fixed vertical axis, means associated with the driving element for transmitting horizontal oscillating movement to one end of said lever, means transmitting horizontal oscillating movement from the other end of the lever to said feeding device, a second lever mounted for rocking movement about a fixed horizontal axis, said second lever having an input arm and an output arm, means connecting the output arm of the second lever to the input arm thereof to render the output arm rigid with the input arm in a vertical plane but to enable the output arm to oscillate in a horizontal plane relative to the input arm, means for transmitting oscillating movement in a vertical plane to the end of the input arm, and means for transmitting vertical oscillating movement from the end of the output arm to said feeding device.

2. An actuating mechanism for the feeding device of a sewing machine comprising a driving

element, a rigid lever mounted for rocking movement about a fixed vertical axis, means associated with the driving element for transmitting horizontal oscillating movement to one end of said lever, means transmitting horizontal oscillating movement from the other end of the lever to said feeding device, a second lever mounted for rocking movement about a fixed horizontal axis, said second lever having an input arm and an output arm, means for transmitting oscillating movement in a vertical plane to the end of the input arm, and means for transmitting vertical oscillating movement from the end of the output arm to said feeding device, said output arm being rigid in a vertical plane to effect the transmission of vertical oscillation, and flexible in a horizontal direction to enable the feeding device to oscillate in a horizontal plane without affecting the input arm of the second lever.

3. An actuating mechanism for the feeding device of a sewing machine comprising a driving element, a cam carried by said driving element, a rigid lever mounted for rocking movement about a fixed vertical axis, means including a cam follower engaging said cam for imparting horizontal movement to one end of said lever about said vertical axis, means transmitting horizontal oscillating movement from the other end of the lever to said feeding device, a second lever mounted for rocking movement about a fixed horizontal axis, said second lever having an input arm and an output arm, means connecting the output arm of the second lever to the input arm thereof to render the output arm rigid with the input arm in a vertical plane but to enable the output arm to oscillate in a horizontal plane relative to the input arm, means engaging said cam for imparting oscillating movement to the end of the input arm, and means for transmitting vertical oscillating movement from the end of the output arm to said feeding device.

4. An actuating mechanism for the feeding device of a sewing machine comprising a driving element, a cam carried by said driving element, a rigid lever mounted for rocking movement about a fixed vertical axis, means including a cam follower engaging said cam for imparting horizontal movement to one end of said lever about said vertical axis, means transmitting horizontal oscillating movement from the other end of the lever to said feeding device, a second lever mounted for rocking movement about a fixed horizontal axis, said second lever having an input arm and an output arm, means connecting the output arm of the second lever to the input arm thereof to render the output arm rigid with the input arm in a vertical plane but to enable the output arm to oscillate in a horizontal plane relative to the input arm, means engaging said cam for imparting oscillating movement to the end of the input arm, and means for transmitting vertical oscillating movement from the end of the output arm to said feeding device, said cam having two opposed partially cylindrical surface portions of different radii, and concentric with the rotation axis of the cam, connected by inclined ram portions and said cam follower and the means for imparting oscillations to the end of the second lever engaging the surface of said cam at regions circumferentially spaced apart, about 90°.

5. An actuating mechanism for the feeding device of a sewing machine comprising a driving element, a cam carried by said driving element, a rigid lever mounted for rocking movement about a fixed vertical axis, a driving carriage mounted on one end of said rigid lever for sliding move-

ment longitudinally of the lever, a cam follower fixed on said carriage and engaging said cam so that rotation of the cam imparts reciprocating movement longitudinally of said lever, a guide element mounted for rotation about an axis parallel to the axis of said lever and provided with a diametrically extending guide slot, means carried by said carriage and extending into the slot of the guide element and operable to impart horizontal oscillating movement of the carriage and the end of the lever carrying the same about said vertical axis, means transmitting horizontal oscillating movement from the other end of the lever to said feeding device, a second lever mounted for rocking movement about a fixed horizontal axis, said second lever having an input arm and an output arm, means connecting the output arm of the second lever to the input arm thereof to render the output arm rigid with the input arm

in a vertical plane but to enable the output arm to oscillate in a horizontal plane relative to the input arm, means engaging said cam for imparting oscillating movement to the end of the input arm, and means for transmitting vertical oscillating movement from the end of the output arm to said feeding device.
